DESIGN FOR A HOUSE COAT

Irving Geist, New York, N. Y.

Application September 15, 1938, Serial No. 79,911

Term of patent 3½ years

To all whom it may concern:

Be it known that I, Irving Geist, a citizen of the United States of America, residing in New York city, in the Borough of Manhattan, county and State of New York, have invented a new, original, and ornamental Design for a House Coat, of which the following is a specification, reference being had to the accompanying drawing, forming part thereof, wherein

The characteristic feature of my design resides in the stitched quiltings on the waist portion of the house coat as shown.

I claim:

The ornamental design for a house coat, substantially as shown and described.

IRVING GEIST.
